UNITED STATES PATENT OFFICE.

FRED W. LEUTHESSE, OF CHICAGO, ILLINOIS.

AIR-VALVE.

1,008,279.

Specification of Letters Patent. Patented Nov. 7, 1911.

Application filed April 4, 1911. Serial No. 618,833.

To all whom it may concern:

Be it known that I, FRED W. LEUTHESSE, a citizen of the United States, residing at Chicago, in the county of Cook and State of Illinois, have invented certain new and useful Improvements in Air-Valves, of which the following is a specification.

The present invention relates to an adjustable seating member for the expandible member, which controls the passage of air and steam into and out of the interior of the valve casing.

The objects of the present invention are, to provide a seating member for the expandible member which is of a nature to be readily adjustable, and which will be provided with a sight opening that will enable the workman assembling the air valve mechanism to determine when this seating member has been brought into proper correlation with the expandible member.

Further objects of the invention are, to so form the seating member as to provide a passage which, in addition to providing a sight opening for the purpose heretofore stated, provides a passage through which steam can pass, whereby the proper adjustment of the seating member can be determined either by looking through the sight opening and seeing where the seating face of the seating member is lying with respect to the end of the expandible member, or by noting the presence of escaping steam through said opening; and a further object of the invention is to provide a seating member which is cheap and simple of construction, and which will have eliminated therefrom all compressible members or sliding members and will consist solely of a ring-like member adjustable in the valve casing.

The invention further relates to the features of construction and the combination of parts hereinafter described and claimed.

In the drawings, Figure 1 is a sectional view of an air valve, showing one form of the seating member of the present invention in operative position; Fig. 2, a view similar to Fig. 1, showing a modified form of seating member; Fig. 3, a view similar to Fig. 1, showing still another modified form of seating member; and Figs. 4 and 5, sectional details showing modified forms of mounting for the expandible member.

The air valve of the present invention is of the general type employed with steam radiators for the purpose of permitting the

air to escape out from the radiator when it is forced out by the entrance of steam thereinto, and to automatically check communication between the interior of the radiator and the outside air after the air shall have been driven from the radiator. This checking is to prevent the outflow or escapement of steam from the radiator for a long period of time, which is obviously detrimental, as it results in a decrease in the amount of heat given off by the radiator.

In air valves of the type in which the seating member of the present invention is employed, it has been the common expedient to equip said air valves with an expandible member which will be susceptible to thermal changes, and to provide a seating member for said expandible member which co-operates with this expandible member to establish and cut off communication between the interior of the radiator and the outside air. It is of the utmost importance in this type of air valve to have the seating member so adjusted with respect to the expandible member as to enable an engagement to be made between these two members after the expandible member has been distended a predetermined amount. If the seating member is not in close enough proximity to the end of the expandible member, there will be maintained a clearance between the two which will not be closed by the distension of the expandible member, which is produced by subjecting it to a certain amount of heat; and hence, there will be a constant leakage of steam from the radiator through the escapement valve. This continued leakage will result in a material decrease in the heating efficiency of the radiator, and where there are several radiators in a system all leaking steam in this manner, it would be impossible to maintain a steam pressure sufficient to produce the proper amount of heat.

Because of the nature of the material of which these expandible members are made, if a too close engagement is made between the seating member and the end of the expandible member, it will result, when the expandible member distends, in a crushing and breaking of the expandible member, and this would, of course, destroy the efficiency of the device, and even if it did not result in an absolute breaking of the expandible member, it would result in a warping or bulging, which would be just as undesirable so far as the further operation of the device is con-

cerned. So it will be seen that extreme caution must be used in the adjustment of this seating member, and that if a proper adjustment is not had, the efficiency of the entire device is destroyed.

It has been the practice in the art to which the present invention relates to use various forms of tension controlled members with these seating members, or to provide a series 10 of movable members which are so arranged that when the proper engagement is made between the expansible member and its seating member, steam issuing from the opening in the seating member will give an indication of such a condition, or the indication 15 will be given by being forced into such a position that no further movement of them by a tool can be accomplished. In this latter construction, however, the operator could 20 not see the position of the parts and so was unable to make the adjustment before the valve left the factory. In both of these cases, the adjustment is determined solely by the movement of certain parts of the 25 seating member for the expansible member. In the present invention these movable parts have been entirely eliminated, and the adjustment can be determined before the valve leaves the factory, which has been impossible 30 in prior constructions, so far as I am aware, because of the fact that it was necessary, in order to get an accurate adjustment, to note the presence of steam issuing from the opening in the seating member, 35 and hence it was necessary to apply the valve to a radiator or some other source of steam supply in order to accurately determine the adjustment.

The device of the present invention is 40 shown as applied to a valve 6, which consists of a casing 7, provided with a nipple 8, adapted to be attached to the radiator, and with a base member 9, to which is entered the end of the exhaust pipe 10; and the casing 45 has secured to its upper end a cap 11, and has located in its interior an expansible member 12.

All of the above described parts are old and well known in the valve art and may 50 be of any desired configuration. They are not claimed as part of the present invention and are merely shown for the purpose of illustrating one type of valve to which the seating member of the present invention may 55 be applied.

The seating member of the present invention is located at the upper end of the valve casing and is in the form of a ring-like member 13, which is provided with an exterior screw-threaded surface 14 adapted to 60 engage with an interior screw-threaded surface 15 on the neck 16 of the valve casing. The ring-like member 13 is provided with a relatively large opening 17. The member 65 may, if desired, be provided with a suitable

notch 18, into which a screw-driver or other instrument is inserted in assembling the seating member in position. The walls 19 of the opening 17, as shown in Fig. 1, are formed on a curve, which provides a sloping 70 seating face 20 at the lower end thereof, which is adapted to seat upon a tapered face 21 upon the upper end of the expansible member. When the face 20 and the face 21 are brought into engagement with one another, a seal is produced, which stops the 75 passage of air out from the valve casing, as well as the escape of steam. It is the maintenance of this engagement between these two faces which requires the fine adjustment 80 of the seating member heretofore referred to.

In the present invention, before the air valve leaves the factory, the workman can, by looking into the hole 17, see when the face 20 of the seating member is in proper 85 relation to the face 21 of the expansible member. That is, he can see when these two faces contact; and then by giving the seating member a short turn, he can space it away from the expansible member a desired 90 distance, so that when the valve is placed upon the radiator, it will operate in an efficient and desirable manner. It will be readily seen that this is of material advantage, 95 since it enables these valves to be adjusted before they leave the factory, and in a quick and efficient manner. Undoubtedly, the manufacturer of valves is better equipped than the user to perform this adjustment so that it will be more efficient in operation, 100 and if this adjustment can be made without the time of subjecting every valve to a steam test, it unquestionably results in a saving of time, and hence a reduction of cost in the 105 construction of the valve.

Of course, the stopping of the flow of steam through the opening 17 will accurately indicate the seating of the face 20 against the face 21, and in this respect the device of the present invention will follow the prior art. But in addition to this, the present invention allows of an observance 110 of the relation of the seating member to the end of the expansible member, so that the adjustment can be made without the steam test, and also eliminates all of the spring-controlled or other movable devices which had formerly been used in conjunction with these escapement valves.

The valve of the present invention is of 115 the simplest form and is extremely cheap of construction, and does not possess a multiplicity of parts which are liable to become disarranged; but possesses every advantage 120 that is found in the structures in the prior art, and possesses the additional advantage 125 of allowing an adjustment to be made before the valve leaves the factory by an observation of the relation of the seating member to the end of the expansible member, 130

which was impossible with the constructions of the prior art with which I am acquainted.

In Fig. 2 a seating member is shown, which is provided with inner sloping faces 22, and which, as shown, are of a straight formation, in place of the curved formation disclosed in Fig. 1.

In Fig. 3 is shown a form of seating member which is provided with a straight inner face 23, which terminates in a shoulder 24, leading from which is a bevel face 25. In this construction a somewhat larger opening is provided.

In Fig. 4 is shown a modified form of holder 26, for supporting the expansible member; and in Fig. 5 is shown another modified holder 27.

All of these modifications work upon the same principle attributed to the form here-
20 tofore described, and the structure shown in Figs. 4 and 5 are merely for the purpose of showing the different forms of expansible member with which this device may be used.

The operation of the device is as follows:
25 When the valve is attached to the radiator, a slight clearance is left between the faces 20 and 21. When steam is admitted to the radiator, it will force the air into the valve casing and out through the passage between the faces 20 and 21. After the air has been exhausted and the steam enters, the entrance of the steam into the valve casing will cause the expansible member to distend until the face 21 is brought into engagement with the face 20 and communication between the interior of the valve casing and the outside air cut off, thus preventing leakage of steam out from the radiator. If leakage of steam is present, the seating member can be lowered until such leakage is stopped, which is an indication that the faces 20 and 21 are in engagement. Before the steam is turned

on, however, the user may, by looking through the hole 17, observe when the seating member is in position, so that it is spaced 45 a trifle away from the end of the expansible member, and this will enable him to determine when the seating member is in correct position, so that the face 21 will engage with the face 20 after the expansible mem- 50 ber has distended the proper distance and automatically cut off the leakage of steam.

I claim:

1. An air valve for radiators, comprising a shell and an expansible member within 55 the shell having an end seating face, and an adjustable ring entered into the upper end of the shell, whereby said ring may be adjustable without removal of the valve from position, the interior face of said ring being 60 configured to provide a seating face for the upper end of the expansible member, the opening in said ring being of a size to furnish a sight opening to enable the co-relation between the seating face of the ring and the 65 end of the expansible member to be viewed, substantially as described.

2. An air valve for radiators comprising a shell and an expansible member within the shell, said member having a tapered end, 70 and an adjustable ring entered into the upper end of the shell, said ring having its inner face tapered to conform to the taper of the upper end of the expansible member, and providing a seat for said member, the 75 ring opening furnishing a sight for positioning said ring in proper co-relation to the end of said expansible member, substantially as described.
